UNITED STATES PATENT OFFICE.

ALFRED JOHN LIVERSEDGE, OF LONDON, ENGLAND.

DIRIGIBLE AIRSHIP.

1,300,746.

Specification of Letters Patent.

Patented Apr. 15, 1919.

Application filed May 7, 1917, Serial No. 166,933. Renewed March 3, 1919. Serial No. 280,490.

To all whom it may concern:

Be it known that I, ALFRED JOHN LIVERSEDGE, a subject of the King of Great Britain, and a resident of London, England, 5 have invented certain new and useful Improvements in Dirigible Airships, of which the following is a specification.

This invention relates to improvements in and connected with dirigible airships, 10 and has reference to the construction of airships, particularly of the rigid type, in which there is provided a framing of metal or other suitable material, and has for its object particularly to provide additional 15 means of defense and offense, and also means to facilitate the escape of the crew, in the event of the airship being obliged to descend at sea. The invention consists broadly in the provision of a turret structure 20 of rectangular box or boat like form adapted to be suitably housed in the upper part of the airship structure under normal conditions, but capable of detachment from the airship at will so that in the event of said 25 airship sinking in the sea the turret can be readily floated off or launched into the water.

In order that my invention may be the better understood reference is made to the accompanying drawings in which Figure 1 is 30 a cross section through the turret boat.

Fig. 2 is a longitudinal vertical sectional elevation, and

Fig. 3 a plan view.

35 Corresponding letters of reference indicate corresponding parts in each of these views.

Referring to these drawings A designates the turret boat, B, B¹ longitudinal girders 40 of the framing of the air ship which girders are connected at the ends by transverse members. C, C¹, C², C³ are radial members which radiate from a central tubular member running the length of the airship. These 45 radial members are connected to the longitudinal girders preferably by steel connections as indicated. D, D¹, D² are hollow chambers made of thin plywood, aluminum sheeting, or other suitable material, and are 50 intended to act as floats. These hollow chambers which are preferably cylindrical are preferably attached to the turret boat by any suitable form of straps. E, E¹ are longitudinal girders which I may make of 55 bamboo with steel connections constructed of steel tube, or other suitable material.

These girders rest at each end on the junction members E² of the girder structure at the four positions indicated by the references F, F¹, F², F³ as shown. They may be 60 tied to these junctions by wire cord or in any other suitable way. They are also attached either by steel connections or simple binding to other members G, G¹, G², G³. G to G³ are in turn connected to the lower 65 members of the longitudinal girders and to the cross members H, H¹. These girders with their ties constitute a cradle in which the turret boat rests as shown, rails being provided on the boat at J, J¹ to keep the 70 boat in position. The turret boat may also be further secured in its position in the airship by straps L tying together the floats D¹, D² and the longitudinal girders B, B¹. These ties are preferably of rope, web strap- 75 ping or other flexible material that admits of being immediately severed by means of a knife. Thus the boat structure normally is firmly secured to the airship, but in the event of the airship falling into the water 80 and sinking, it is only necessary to cut the straps tying the boat to the longitudinal girders and as the water rises through the structure the boat will be floated off. K is a ladder passing up through the body of 85 the airship and giving access to the turret boat.

I do not limit myself either to a particular form of boat or to any particular means of securing the boat in position. It is ob- 90 vious that various modifications may be adopted, while retaining all the essential features of the invention. It will be appreciated that the boat, raft or other floatable structure may be kept provisioned and may 95 be utilized normally as a platform for guns, searchlights or like accessories.

What I claim and desire to secure by Letters Patent is:—

1. In dirigible airships, an upper struc- 100 ture rigid with the airship structure, a floatable structure adapted to be housed within the rigid structure, longitudinal girders on the rigid structure for supporting said floatable structure, and temporary lashings for 105 detachably securing said floatable structure to said rigid structure.

2. In dirigible airships, an upper rigid structure forming part of the airship and composed of longitudinal and transverse 110 girders supported by struts, a floatable structure in the form of a boat, floats at-

tached to the boatlike floatable structure, and lashings for temporarily attaching the floats to the rigid structure.

3. In a dirigible airship, a detachable and floatable boatlike structure, a rigid girder structure permanently attached to and forming part of the airship structure and forming a cradle to receive the floatable structure, longitudinal girders supporting the hull of

the floatable structure, cross stays supporting said longitudinal girders, further longitudinal girders adjacent the gunwale of the floatable structure, and lashings for temporarily attaching the floatable structure to these further longitudinal girders. 10 15

In testimony whereof I affix my signature.

ALFRED JOHN LIVERSEDGE.

Copies of this patent may be obtained for five cents each, by addressing the "Commissioner of Patents Washington, D. C."
